J. A. Morrell.

Uterine-Supporter.

No 75694

Patented Mar. 17, 1868.

United States Patent Office.

JAMES A. MORRELL, OF CHICAGO, ILLINOIS, ASSIGNOR TO HIMSELF AND
ISAAC SIMMONS, OF BALTIMORE, MARYLAND.

Letters Patent No. 75,694, dated March 17, 1868.

IMPROVEMENT IN UTERINE SUPPORTERS.

The Schedule referred to in these Letters Patent and making part of the same.

TO ALL WHOM IT MAY CONCERN:

Be it known that I, JAMES A. MORRELL, of Chicago, in the county of Cook, and State of Illinois, have invented a new and useful Improvement in Uterine Supporters; and I do hereby declare and make known that the following is a full, clear, and exact description of the same, reference being had to the accompanying drawings, and the letters and figures marked thereon, which form part of this specification.

My invention consists in supporting the pessary, which receives the "os uteri," upon its stem or support, by means of a spring, or its equivalent, so as to insure an elastic, yielding movement to the pessary, and at the same time to sustain the womb in the desired position without any rigid upward-bearing pressure upon the same.

My invention further consists in so constructing the stem, which supports the said pessary of a uterine supporter, that the same can be lengthened or shortened, so as to place the pessary farther up or lower down in the vaginal passage, thus adjusting the instrument to suit different persons and different cases.

To enable those skilled in the art to understand how to construct and use my said invention, I will proceed to describe the same with particularity, making reference, in so doing, to the aforesaid drawings, in which—

Figure 1 represents a perspective view of my invention.

Figure 2 is a side view of the supporter; and

Figure 3 is a vertical central section of the same.

Similar letters of reference in the several figures denote the same parts of my invention.

A represents the pessary, which is composed of hard or soft rubber, or any other material appropriate for the purpose, and is provided with a recess or cavity upon its top, marked *a*, to receive the "os uteri," and with one or more perforations, *b*, to allow the fluids passing from the womb to escape. Into the lower part of the pessary a tube, *B*, is screwed, securing the same thereupon in such a manner as to permit it to be removed, if desired. Within said tube *B* is arranged a spiral spring, *C*, of sufficient strength and elasticity to sustain the weight of the pessary and its supporting-tube *B*, and to permit the required yielding movement of the same when in use, the upper end of said spring being secured to the upper end of the tube by a pin, *c*, or otherwise, as shown. Below said spring *C*, and sliding within the tube *B*, is a second tube, *D*, which is retained in position by means of a rod, *E*, having a head upon its lower end, and passing up through said tube *D*, as shown, the upper end of said rod being provided with a cross-arm, *d*, or a screw fitting between the coils of the spring *C*, so that the rotations of said rod, which may be effected by grasping the head below the tube *D*, will slide the tube *D* up within the tube *B*, to shorten the stem of the pessary, or down, so as to lengthen said stem, as may be preferred or desired. There is also a collar, *e*, upon said rod, upon which the lower end of the spring *C* rests, as shown.

It will be observed that, however high the cross-arm *d* may be turned up in the coil of the spring, the compression of the spring takes place below the point at which *d* may stand, leaving the upper part of the spring free to operate as desired.

A stem-support, *F*, is attached to the lower end of the tube *D*, by a ball-and-socket joint, *J*, or some other suitable hinge or joint, as shown, to allow the supporter to open, as indicated by the dotted lines in fig. 2, to adapt it to persons of different abdominal configurations; or said stem-support may be connected to the stem of the pessary rigidly, if desired. At the opposite end of the stem-support is a ring, or its equivalent, whereby the device is suspended upon an elastic strap, *H*, which is secured in any suitable manner, as shown, to a belt, *L*, worn around the person, or to any equivalent therefor.

It is obvious that a uterine-supporter, in which the pessary is supported upon a spring or elastic stem, would be a very great improvement, even though the stem were not susceptible of being lengthened or shortened; and, also, that the so constructing of the stem that it may be lengthened or shortened, is a valuable improvement, even though the pessary has no elastic support upon its stem; and, also, that the jointed attachment of the stem to the stem-supporter would be of great convenience, even if applied to uterine supporters of the ordinary kinds in use.

It is also obvious that many mechanical equivalents may be used, whereby the desired results may be

obtained, either separately or in combination, and I do not desire to limit myself to the particular mechanical means herein shown and described.

Having described the nature and construction of my invention, I will now specify what I claim, and desire to secure by Letters Patent.

1. I claim the combination of a pessary, A, tube B, spring C, tube D, and rod E, arranged and operating substantially as and for the purposes specified.

2. I claim connecting the stem of a uterine supporter to the stem-supporter by a hinge or joint, so as to operate substantially as described.

3. I claim the combination of a pessary, A, and its stem, constructed substantially as described, with the jointed arm F, and the elastic strap H, arranged and operating in the manner and for the purposes specified.

JAS. A. MORRELL.
